UNITED STATES PATENT OFFICE.

ROBERT KAUFMANN, OF CINCINNATI, OHIO.

DISPLAY-RACK.

SPECIFICATION forming part of Letters Patent No. 401,653, dated April 16, 1889.

Application filed August 6, 1888. Serial No. 282,088. (No model.)

To all whom it may concern:

Be it known that I, ROBERT KAUFMANN, of Cincinnati, Hamilton county, Ohio, have invented a new and useful Display or Cloak

5 Rack, of which the following is a specification.

My invention relates to folding rack or frame to facilitate the display of cloaks and like articles of apparel in stores. The rack is so constructed as to be capable of being

10 adjusted to any desired slope for proper exhibition of the goods or of being folded into a very compact form for storage or shipment.

In the accompanying drawings, Figure I is a perspective view of my rack set up in position for use. Fig. II is a top view, and Fig. 15 III is a longitudinal section of my folded rack without the base.

11 are two stiles, which are united at their upper ends by an arch, 2, preferably of the 20 represented curved form, and at their lower ends by a rundle, 3, whose ends are journaled in the stiles, as at 4.

5 is a web of any woven fabric—such as of linen, cotton, or wire—one end of which is 25 wrapped around and securely tacked to the arch 2. The other end of the web is wrapped around and tacked to the rundle 3, which, having been rotated until the web is stretched taut, is made fast in the stiles by means of 30 pins or screws 6. Hinged to the stiles, as at 7, are two folding props, 8 9, of which prop 8 has notches 10, which, receiving and holding the cross-piece or stretcher 11 of prop 9, coacts therewith to hold the rack proper to 35 the desired slope.

My rack, as above described, is complete in itself, but for some kinds of display is preferably hinged, as at 12 12, to a base, 13, equipped with casters 14.

For purpose of stowage or transportation 40 the rack is capable of being folded into the exceedingly flat condition shown in Figs. II and III, either with or without the web and with or without the base.

It is found to be advantageous to have one 45 end of the fabric secured as in my invention, inasmuch as the fabric is apt to stretch and become slackened, when it may be readily stretched by removing the pins or screws and turning the rundle, and then reinserting the 50 screws.

I claim as new and of my invention—

The display-rack consisting of the stiles 1 1, connected by arch 2 and rundle 3, the latter being journaled in the stiles, the 55 fabric 5, secured at top to the arch and wound at bottom on the rundle, the pins 6, for securing the rundle, the prop 8, having notches 10, and prop 9, having cross-piece 11, which rests in the notches, said props being hinged, as at 60 7, substantially as herein explained.

In testimony of which invention I hereunto set my hand.

ROBERT KAUFMANN.
